UNITED STATES PATENT OFFICE.

ISIDOR KITSEE, OF PHILADELPHIA, PENNSYLVANIA, ASSIGNOR OF ONE-HALF TO WILLIAM J. LATTA, OF PHILADELPHIA, PENNSYLVANIA.

ELECTRIC TELEGRAPHY.

No. 872,824.

Specification of Letters Patent.

Patented Dec. 3, 1907.

Application filed March 16, 1905. Serial No. 260,386.

To all whom it may concern:

Be it known that I, ISIDOR KITSEE, of the city and county of Philadelphia, State of Pennsylvania, have invented certain new and useful Improvements in Electric Telegraphy, of which the following is a specification.

My invention relates to an improvement in electric telegraphy, and has more special reference to repeating or translating for true reversals, such for instance as are described in United States Letters Patent No. 777,259, granted to me December 13th, 1904.

In telegraphing with true reversals the conventional signs of dots and dashes have to be replaced by an arrangement whereby one of these signs is characterized by one impulse, therefore one dot, and the second sign is characterized by two impulses in quick succession, therefore two dots in close proximity to each other. To receive and relay such impulses I have recourse to the devices and arrangements as will hereinafter be more fully described, illustrated in the drawing and more clearly pointed out in the claims following the specification.

The accompanying drawing illustrates my invention in partial plan and partial dia-grammatic view.

A is the receiving device and B and B¹ the translating devices. The receiving device A is a polarized relay of a sensitiveness required for the line of transmission, and such line may be either an overland or submarine cable. The construction of such a polarized relay does not form part of this my invention and it is therefore only necessary to point out such features of this relay as are necessary for the working of my system, and in this relay the polarized armature is designated as *a*, the coils as *d*, and the points of contact as *b* and *c* respectively. One terminal of the coils *d* is connected through binding-post 1 to the line of transmission 2; the second terminal of the coils *d* is connected through binding-post 3 and wire 4 to the ground *g*. I have not shown here any of the devices customarily inserted in such lines or between such ground and lines, as my invention does not contemplate a change in these special features in such lines or grounds.

e and *f* are two sources of current, here shown as batteries connected oppositely as to each other, the positive pole of *e* con-

nected through wire 7 to contact *b*, the positive pole of *f* connected through wire 8 to contact *c*; the armature *a* connected through binding-post 5 and wire 6 to the other poles of both batteries.

Of the translating devices, B is a polarized relay preferably of a construction similar to that of relay A, but as B is only locally connected it does not require the sensitiveness necessary for A. In this relay B *a*¹ is the armature, *d*¹, *d*² the coils, *b*¹ and *c*¹ the two contact-points respectively.

*B*¹ is an electro-magnet, the armature of which is designated as *k*, the spring by *l*, and the two contacts in close proximity to said armature as *m* and *n* respectively.

The electrical connections between the receiving relay and the translating devices is as follows:—The point *c* of device A is connected through wire 10 and binding-post 11 with one terminal of the coils of the device B, the other terminal of these coils being connected through binding-post 12 and wire 18 with one terminal of the electro-magnetic device B¹, the other terminal of said device connect through wire 9 with the binding-post *b* of the device A. The contact *b*¹ of the device B is connected through wire 15 with one pole of a source of current, here shown as the positive pole of the battery *h* grounded at *g*; and the contact *c*¹ is connected through wire 16 with the opposite pole of a second source of current, here shown as the negative pole of battery *i*, also grounded at *g*. The armature *k* of the device B¹ is connected through wire 14 and binding-post 13 to the armature *a*¹ of the device B. The contact *m* is connected with the line of transmission 2^a to which the received messages are to be automatically transferred. The working of this arrangement is as follows:—Through the manipulation of the key connected to the line 2 the armature *a* of the device A is alternately brought in contact with the contacts *b* and *c*. Through the contact of the armature *a* with contact *c*, as is illustrated in the drawing, the battery *f* is short-circuited; at the same time a circuit is established consisting of the battery *e*, wire 7, contact *b*, wire 9, coil of device B¹, wire 15, binding-post 12, coils *d*¹, and binding-post 11 of the device B, wire 10, contact *c*; armature *a*, binding-post 5 and wire 6 of the device A, which wire carries the current back to the negative pole of the bat-

battery i . Through the establishing of this circuit, the armature a^1 of B is moved towards and in connection with one of the contacts b^1 and c^1 and it is supposed as is indicated in the drawing, that the armature is moved towards c^1 and rests against this contact, and as c^1 is connected through 16 with the negative pole of the battery i , grounded at g , a circuit would have been established including the line of transmission 2^a were it not for the fact that through the establishing of the first named circuit the core of the electro-magnet B will have been energized, thereby drawing the armature k away from the contact m and against the stop n . It is now supposed that the operator of line 2 sends a second impulse over the line. As this second impulse will have to be of a polarity opposite to the polarity of the first impulse (to make a true reversal) the armature a of device A will move from c to b . In that period, that is, from the time that the contact between c and the armature a is broken till the period when 25 the contact between the armature a and point b is made, the circuit including the coil of B^1 will be broken and the armature k relieved from its magnetic influence will, impelled by the force of the spring l , be drawn towards and in contact with the point m , thereby making electrical connection with the line of transmission 2^a ; but, the armature a^1 of the device B will still rest on the point c^1 and if the line 2^a is 30 grounded, as is usual, at its distant terminal, it is obvious that an impulse will flow in the direction from the positive pole of i grounded at g , distant ground, through the line of transmission 2^a , contact m , armature k , wire 14, binding-post 13, armature a^1 , contact c^1 , wire 16, back to the negative pole of i , and this impulse will flow during the whole period that the armature rests at c^1 , and this period will last till, through 35 the contacting of a with b the current-flow through d and d^1 is reversed. When such reversals of the current-flow will take place, then the armature a^1 of the device B will move from c^1 towards and in contact with b^1 , thereby establishing a circuit between the armature a^1 and the positive pole of the battery h grounded at g ; but as at the same time the core of B^1 is energized, the armature will be drawn away from m breaking its contact with the line of transmission 2^a . If now the operator at line 2 sends again an impulse of opposite polarity over the line, the armature a of the device A will 40 break its connection with b and will travel towards c ; during this travel the circuit including the coil of B^1 will be broken, the armature will again be drawn towards and in contact with the point m and as the armature a^1 of B still rests at b^1 , it is obvious 45 that a circuit will be established with the

battery h , whereby a current will flow from the positive pole of h , through wire 15, contact b^1 , armature a^1 , binding-post 13, wire 14, armature k , contact m , line of transmission 2^a , distant ground back to the ground g , and to the negative pole of h . The flow of this impulse is therefore opposite to the flow of the preceding impulse and will last during the whole period that armature a travels from b to c and will cease as soon as a makes contact with c . Thus it will be seen that:

1. Every impulse sent over the line 2 will move the armature a of the device A towards and in contact with one of the contacts c or b respectively.

2. Through the contacting of the armature a with one of these contacts c or b , the armature a^1 of the device B is moved towards and in contact with one of the contacts c^1 or b^1 respectively.

3. The contacting of the armature a^1 with one or the other of these contacts c^1 or b^1 would connect the second line of transmission 2^a with one of the batteries h or i were it not that as soon as the circuit including the electro-magnet B^1 is made, the contact between its armature k and point m is broken.

To effectually connect the batteries i or h with the line of transmission 2^a , it is therefore not only necessary that the armature a^1 of the device B shall connect with one of the contacts c^1 or b^1 , but it is also necessary that at the same time the electro-magnet B^1 should remain deenergized so as to allow the armature k to remain in contact with the point m , and this can only take place during the time that the armature a of the device A is traveling from one contact to the other contact, and the time period for each impulse flowing over the line 2^a will be equal to the time period that elapses while the armature a is traveling from one of said contacts to the second of said contacts, and as this armature changes its direction through every impulse sent over the line 2 and as the armature a^1 of the device B follows this change in direction, it is obvious that the impulse sent over the line 2^a will not only be of the same duration, but will always be of alternate polarity.

It is obvious that the arrangement may be altered to suit requirements, but in all cases polarized relays should be employed and the connections be made in such a manner so as to allow only a predetermined time period for the transmission of impulses through line 2^a .

It is suggested that in the practical working of this device it should be agreed upon between both operators that, after sending a message, one impulse shall always be transmitted over the line, this impulse to be of a direction so as to move the armature a of the device A to the contact c or b , as agreed upon. It is supposed that the contact agreed upon is the point c , and it is supposed that to send

the armature *a* in contact with *c* it requires the transmission of a negative impulse over the line. It should therefore be agreed between the two operators that in sending a message the first impulse to be transmitted should always be of positive polarity.

Having now described my invention, what I claim as new and desire to secure by Letters Patent is:—

10 1. In combination with a line of transmission two polarized relays, one relay connected to said line, the second relay connected to the contacts of the first relay, an electro-magnet, a second line of transmission and means to connect through the movements of the armature of said electro-magnet said second line to a source of current.

20 2. In telegraphy with reversals, a polarized relay connected to the line of transmission, localized sources of current for said relay, a second relay operatively connected to said first relay, an electro-magnet, a second line of transmission and means whereby through the movements of the armatures of 25 said relays, the electro-magnet is energized or deenergized thereby connecting or disconnecting the second line of transmission from a source of current.

30 3. In telegraphy means to receive true reversals, means to relay said reversals, means to translate said reversals into Morse characters and means to relay said characters on to a second line said aforesaid means embracing two polarized relays and a translating device.

35 4. In telegraphy, a line of transmission, a polarized relay connected to said line of transmission, sources of current locally connected to said relay, a second polarized relay and electro-magnet connected operatively 40 to said first relay, sources of current connected operatively to said second relay, a

second line of transmission in operative relation to parts of said electro-magnet and means whereby through the movement of 45 the movable part of the first relay the movable part of the second relay is connected with one or the other of the poles of a source of current and through parts of the electro-magnet with said second line of transmission. 50

5. In combination with two lines of transmission two polarized relays and an electro-magnet in operative relation with each other and said two lines, a source of current locally connected to one of said relays, a source of 55 current locally connected to the second of said relays, and means whereby the movement of the movable part of the first relay are repeated by the movement of the movable part of the second relay and whereby 60 during the travel of the movable part of the first relay electrical connections are established between parts of the electro-magnet and one of the lines of transmission, said parts of the electro-magnet adapted to be 65 brought in electrical connection with one or the other of the poles of the source of current in operative relation to the second relay.

6. In telegraphy, a cable, a polarized relay inserted therein, a second polarized relay and translating device, a circuit from said first relay to said second relay and translating device, two sources of current related to said second relay, a second cable, all related in a manner so as to translate into readable characters and relay to the second cable the impulses impressed upon the first cable. 70 75

In testimony whereof, I hereby sign my name in the presence of two subscribing witnesses, this first day of March, A. D. 1905.
